UNITED STATES PATENT OFFICE

151,878

DESIGN FOR A PROJECTOR FOR HANDLING TRANSPARENT PLATES

Harold G. Fitz Gerald, Los Angeles, Calif.

Application August 20, 1947, Serial No. 140,966

Term of patent 14 years

(Cl. D61--1)

To all whom it may concern:

Be it known that I, Harold G. Fitz Gerald, a citizen of the United States, residing in the city of Los Angeles, county of Los Angeles, and State of California, have invented a new, original, and ornamental Design for a Projector for Handling Transparent Plates, of which the following is a specification, reference being had to the accompanying drawings, forming a part thereof.

Fig. 1 is a perspective view of the projector for handling transparent plates showing my new design, showing the top and one end of the projector from one side thereof, and Fig. 2 is a perspective view of the projector showing the bottom and the other end from the other side thereof.

I claim:

The ornamental design for a projector for handling transparent plates, as shown.

HAROLD G. FITZ GERALD.
